LOCKING DEVICE FOR CRANE HOOKS

Karl Clodfelter, Blue Island, Ill.

Application April 11, 1936, Serial No. 73,927

4 Claims. (Cl. 294—82)

My invention relates to the art of handling materials by a crane and particularly to a safety device adapted to lock a crane hook against rotation when used for supporting a lifting magnet.

A magnet is used for handling materials of a certain type, the magnet being attached by a ring to the crane hook. There is, however, a tendency for the magnet and its load to rotate while the load is being transported and such rotation will frequently be continued to such an extent that the conducting wires will be twisted off, thus de-energizing the magnet and dropping the load. This is a matter of considerable danger and, of course, could be avoided by constructing the crane hook and block in such manner that rotation would not be permitted. This, however, would render the apparatus useless for other purposes for which the crane is used in which rotation is desirable.

The device of my invention is intended to adapt the hook for both uses, the hook being locked when a magnet is supported thereon and free to rotate in other uses.

The invention will be more readily understood by reference to my accompanying drawing; in which,

Fig. 1 is an elevation of a crane hook and block with a lifting magnet depending therefrom.

Fig. 2 is a plan view of the block and hook with my improvement applied thereto;

Fig. 3 is an end view thereof; and,

Fig. 4 is a side elevation partly in section.

In Fig. 1 a conventional construction is shown including wire ropes 10, sheaves 11, supporting plates 12, a hook block 13, hook 14, lifting magnet 15 and connecting cable 16. The hook shank 14 has a portion 17 of reduced diameter at its upper end projecting through the hook block 13 and terminating in a threaded portion carrying a hexagon nut 18 which is pinned to the shank.

A washer 18a may be interposed between the nut and the hook block. This construction permits the hook to rotate freely in the block. My construction includes a plate 19 in the form of a saddle, the plate having side flanges 20, shown in the instance as separately formed and joined to the plate by rivets, 21, the flanges conforming to the contour of the hook block and serving to fit the saddle closely thereon. Bolts 22 and cross-pieces 23 at the two ends of the structure serve to clamp the saddle securely in place.

The plate or saddle has a center opening that is undercut, thereby providing a flange 24, that borders the opening. Seated in the opening is a disc 25, having a marginal flange 26, that under-

lies flange 24, of the plate. A second disc 27, overlies the plate and is secured to the first disc by rivets 28. Both discs are provided with a hexagonal opening nicely fitting the nut 18. Both the flanges of the discs and the plate are provided with a plurality of registering apertures 29, located at different angular points, as shown, and when it is desired to use the crane hook in connection with a lifting magnet one or more pins 30 are inserted in the openings as shown in Fig. 4, thus securely locking the hook and block against relative rotation. The pins may be carried on a chain, not shown, in order to be readily available for use when needed.

It will be seen that with my device in place, the crane may be operated in its usual manner and the hook permitted to rotate freely. When, however, a magnet is to be supported one or more of the pins is slipped into place, thereby locking the parts against relative rotation. The device is so constructed that it may be quickly and easily applied to existing crane blocks with very short interruption of operations.

I claim:

1. The combination with a hook block, of a saddle fitted thereover and clamped thereto, a disc having an annular flange underlying a portion of said saddle, said disc having a noncircular axial opening, a hook shank having a head portion fixed thereon and shaped to fit said axial opening, said saddle and flange having registering openings, and a pin adapted to enter said openings to prevent relative rotation between said hook and block.

2. In combination, a hook block and a hook shank projecting through the block and a nut fixed on the shank, a saddle overlying said block and clamped thereto, said saddle having a central opening, a disc in said opening with its periphery underlying a portion of said saddle, said disc having a central opening shaped to receive the hook nut, said disc and saddle having registering openings, and a pin adapted to enter said openings and when in place to prevent relative rotation between hook and block.

3. In combination, a hook block and a hook shank projecting through the block and a nut fixed on the shank, a saddle overlying said block and clamped thereto, said saddle having a central opening, a disc in said opening with its periphery underlying an integral flange that borders said central opening in the saddle, said disc having a central opening shaped to receive the hook nut, said disc and saddle having registering openings, and a pin adapted to enter said open-

ings and when in place to prevent relative rotation between hook and block.

4. In combination a hook block and a hook shank passing vertically through the same, a non-round fastening element secured to the shank above the block, a plate having depending side flanges fitting over the side edges of the block, said plate having a central opening, a disc hav-

ing a non-round aperture fitting the hook fastening element, said disc underlying a portion of the plate with capacity for rotation, said plate and disc having registering openings, and a pin adapted to enter said openings to prevent relative rotation between hook and block.

KARL CLODFELTER.
